UNITED STATES PATENT OFFICE.

GEORGE F. ORMSBEE, OF SMITH CENTER, KANSAS, ASSIGNOR OF ONE-HALF TO EDSON F. YALE, OF LINCOLN, NEBRASKA.

WELL-BORING MACHINE.

1,366,826.

Specification of Letters Patent. Patented Jan. 25, 1921.

Application filed August 12, 1920. Serial No. 403,064.

To all whom it may concern:

Be it known that I, GEORGE F. ORMSBEE, a citizen of the United States of America, and a resident of Smith Center, Smith 5 county, State of Kansas, have invented certain new and useful Improvements in and Relating to Well-Boring Machines, of which the following is a specification.

This invention relates to certain improvements in and relating to well boring machines; and the objects and nature of the invention will be readily understood by those skilled in the art in the light of the following explanation of the accompanying drawings illustrating what I now believe to be the preferred embodiment or mechanical expression of my invention from among other forms, constructions and arrangements within the spirit and scope thereof.

20 An object of the invention is to provide a portable well boring machine having a power unit mounted on the machine and transportable therewith in operative connection with the boring mechanism; the arrangement of power unit and boring mechanism being such, that a single operator can readily control the machine during boring operations.

25 A further object of the invention is to provide a well boring machine in which the boring implement operating mechanism carries the boring implement raising and lowering mechanism and is suspended from a single point at the top of a stationary frame and rotatable around such point of suspension as an axis.

30 A further object of the invention is to provide a well boring machine in which the boring implement during boring operations is supported independently of its operating mechanism and is rotated by contact therewith; the arrangement being such that, the implement can be readily raised and lowered independently of its operating mechanism to add additional lengths to the implement or detach said lengths therefrom, and when so raised and lowered its weight is carried by the operating mechanism suspended from a stationary frame.

35 A further object of the invention is to provide improved bearing and centering means for the boring tool operating mechanism which means also provides a guide for the boring tool.

40 With these and other objects in view, my

invention consists in certain novel features in construction, and in formation and arrangement of parts as more fully and particularly set forth and specified hereinafter.

Referring to the accompanying drawings: 60

Figure 1 is a side elevation showing particularly the driving mechanism.

Fig. 2 is an end elevation showing parts of the machine in vertical section, to show the arrangement of boring implement operating mechanism and boring implement. 65

Fig. 3, is a longitudinal vertical section of a machine of my invention.

Fig. 4, is a horizontal section taken on the line 4—4 of Fig. 2. 70

Fig. 5 is a detail view of the hoisting mechanism and the driving connections therefor.

Fig. 6, is a detail view of the extension member mounted on the boring implement. 75

The present invention provides a wheeled supporting structure upon which is mounted a stationary tower having a rotary frame suspended from its upper end and depending through a central opening in the supporting structure. 80

A power unit is mounted on and carried by the supporting structure and is adapted to rotate the suspended frame. An auger, in operative position supported independently of the rotary frame, extends upwardly through the central opening in the supporting structure and within the rotary frame. The auger is provided with an arm which extends radially therefrom into the path of rotation of the suspended frame, so that, when the frame is rotated it bears against and contacts with the radial arm on the auger, and rotates the auger. Mechanism is mounted on the suspended rotary frame to raise and lower the auger, or other boring tools, and when raised or lowered the auger, or other tools, are supported by the rotary frame. 85 90 95

In the particular example of my invention, illustrated in the accompanying drawings, I show a supporting structure 2 with wheels 3. A bed 1 is mounted on and spaced a distance above the supporting structure 2. 100 Any form of supporting structure, or arrangement of the bed 1 may be utilized without departing from the spirit and scope of the invention.

A stationary tower 4 is mounted on and fixed to the bed 1 by suitable fastening 105 110

means, such as the angle irons 5. The frame 4 comprises uprights 6 extending upwardly and inwardly to a point approximately directly above the center of base 1 and are 5 connected and maintained in rigid, spaced relation at their upper ends by cross pieces 7, or the like. Cross bracing 8 is provided between the uprights 6 to maintain the frame in upright, rigid position on the base 10 against all strains and stresses to which the frame may be subjected.

A cross bar 9 is rigidly fastened across the top of tower 4 to opposite cross pieces 7. The cross bar 9 is provided with a vertical 15 central bore adapted to receive the bolt or axle 10, the arrangement and object of which appears hereinafter.

The central portion of base 1, between the uprights 6 of the tower 4, is cut out to form 20 an enlarged central unobstructed opening 13 the center of which is directly below and in vertical alinement with the vertical bore in the cross bar 9.

A vertical frame 14 is suspended at its upper end from the cross bar 9 of tower 4. The frame 14 is formed of uprights 15 inclined inwardly and converging together at their upper ends, at which point they are fastened a distance apart by a substantially U shaped 25 iron member or strap 17 having its legs extending downwardly and bolted to the uprights 15. The strap 17 extends across the ends of the uprights 15 and maintains them rigidly secured in proper spaced relation. 30 Suitable cross bracing 19 is provided between uprights 15 to maintain the uprights against strains and stresses and provide a rigid rotary frame. The portion of the strap 17 which extends across the ends of the uprights 15 is provided with a centrally located bore.

An axle 10 having the enlarged end 18^a and revoluble bearing 18 extends upwardly 45 through the bore in strap 17 and the bore in cross bar 9 a distance beyond the bar 9. The axle 10 is secured in the bore in cross bar 9 by a washer 12 and nut 11 bearing upon the upper surface of bar 9. The frame 14 is suspended from axle 10 on the bearing 18 50 and is rotatable around the axle 10 as an axis.

The uprights 15 depend downwardly through the opening 13 in the bed 1 and terminate a distance above the top of the 55 supporting structure 2. A circular, unobstructed opening 2^a is cut through the supporting structure 2, directly below, and with its center in vertical alinement with the center of the opening 13 and the axle 10 at the 60 top of tower 4. The opening 2^a is of sufficient diameter to permit the passage of boring tools of the required size therethrough, and is provided with anti friction bearings 25, or the like, around its inner edge or bearing 65 surface. A gear wheel 20 is attached

rigidly to and suspended from the ends of the uprights 15 and a distance above the floor or base of the supporting structure 2. The gear 20 is provided with spokes 21 and a hub 22. The hub 22 extends downwardly 70 a distance below the wheel and provides a sleeve or rim 24. The hub 22 is centrally open and unobstructed to form a circular passage extending through the gear 20 and rim 24. The sleeve or rim 24 extends into the 75 opening 2^a of the supporting structure 2 and provides a centering and guiding axle, rotatably confined in the opening 2^a and bearing against the roller bearings 25, to maintain the lower end of frame 14 and gear 20 against 80 lateral movement.

A covering 70 is securely and rigidly bolted, or otherwise attached on the upper side of wheel 20 by means of bolts, or the like 71, fastened to the spokes 21. Cross 85 beams 72 are fastened on the covering 70 and extend upwardly through the opening 13 a distance above the upper surface of the bed 1. A platform 16 is secured to and supported by the cross beams 72 and extends 90 a distance beyond the opening 13 and over the bed 1. The platform 16 is provided with a central, circular unobstructed opening therethrough, the center of which is in vertical alinement with the axle 10 and the center of the opening through the hub 22 and depending rim 24 of the gear 20. Platform 16 provides a cover for the opening 13 to protect the gear 20 and supporting structure 2 and further provides a place for the operator to stand during boring operations. 95 100

A guide plate 60 is secured to the platform 16 by the hinges 61 and in lowered position the free edge of the plate extends slightly beyond the center line or diameter of the 105 opening. A notch or cut out portion 62 is provided at the center of the free edge of the guide plate, which notch when the plate 60 is lowered position is in alinement with the center of the opening and is adapted to 110 receive and maintain the vertical boring rods attached to the auger in vertical alinement. In raised position the plate 60 is completely clear of the opening 16^a, leaving the opening unobstructed for the passage of an 115 auger therethrough.

A windlass or hoisting mechanism is mounted on the rotary frame 14 intermediate the platform 16 and the top of the frame. This mechanism comprises a winding drum 27 provided with a gear 28 and a drive shaft 29 provided with a pinion 30 meshing with the gear 28. The drum 27 and shaft 29 are mounted in suitable bearings on opposite uprights 15 of the frame 14, and 120 are so positioned as to be on one side of the center of the opening 16^a of the platform 16 to provide an unobstructed passage for the auger or boring tools in raising and lowering them, from and to operative position. 125 130

The end of shaft 29 opposite pinion 30 extends a distance beyond the frame 14 terminating in a squared end portion 31. A pulley 32 is mounted between opposite uprights 15 at the top of frame 14 and below the axle 10. A hoisting cable 52 is attached to the winding drum 27 and passes up over pulley 32 with its free end provided with a hook or the like 53 adapted to be attached 10 to a boring tool.

A power unit P is mounted upon one end of the bed or base 1 of the truck 2. Suitably journaled in bearings mounted along one side of the frame 4 is the driving shaft 15 33 provided at one end with a driving pulley 34 and at its opposite end with a bevel gear 35. The pulley 34 is connected with the power unit by a belt or the like 36, and a clutch mechanism operated by the hand lever 20 37, is adapted to throw the pulley 34 into and out of operative relation with the power unit P.

A rectangular centrally open plate 38 is mounted upon a frame work on the stationary frame 4 which framework is formed of the vertical beams 39 fastened at their lower ends to the bed 1 and at their upper ends to a horizontally disposed beam 40. The plate 38 is provided with alined, vertical bearings 41 in which is mounted the vertical shaft 42. Intermediate the bearings 41, shaft 42 is provided with a bevel gear 43 in mesh with the bevel gear 35 on the drive shaft 33. The vertical shaft 42 extends a distance downwardly below the base 1 and is provided at its lower end with the pinion 44 in mesh with the gear 20 of the rotary frame 14. A clutch mechanism 45 is interposed in shaft 42 between the pinion 44 and the bearing plate 40 38, by means of which the lower part of shaft 42 with the pinion 44 can be disengaged from operative relation with the upper portion of shaft 42. A manually operated lever 46 is adapted to throw the clutch 45 into and 45 out of engagement with the lower part of shaft 42 and pinion 44.

The upper end of shaft 42 is provided with a bevel gear 47 in mesh with a bevel gear 48 mounted on a short shaft 49 which is journaled in a bearing on the upper edge of the beam 40. The shaft 49 is mounted at an angle so that the driving shaft 29, mounted on the frame 14, will aline therewith when its squared end is opposite the end of the short shaft 49. A square sleeve 50 is mounted to slide on the shaft 49 and when the shaft 29 of the winding mechanism is opposite shaft 49, the sleeve 50 can be slid onto the squared end of shaft 29 and form 55 a driving connection between shaft 49 and shaft 29 on the rotary frame.

A boring tool or auger 51 in operative position rests upon the ground and extends upwardly through the opening 2^a in the supporting structure 2, the open hub 22 and

rim 24, the cut away portion in the base 1, and the central opening 16^a in the platform 16. The free end of the hoisting cable 52 is provided with a suitable hook or other attaching means 53 which is fastened to the 70 upper end of the auger 51.

Referring particularly to Fig. 6 of the drawings, the extension member or arm 54 is shown which is adapted to be attached to the upper end of the auger. The arm 54 is provided at one end with a hooked portion 55 which is formed to fit the square end of the boring tool. A screw bolt or the like 56, passes through a hole 57 in the bill of the hook and is adjustably mounted in a screw 80 threaded hole 58 in the extended or body portion of the member 54.

The operation of a boring machine embodying my invention described herein, is 85

The guide plate 60 is raised and swung back from the opening 16^a to leave the opening unobstructed. The auger 54 is placed in position resting on the ground and extending upwardly through the gear 20, base 1, and 90 platform 16, and the hoisting cable 52 is attached to the end of the tool by the hook 53. An extension member or arm 54 is placed over the squared end of the auger and the bolt 56 is adjusted so that arm 54 is 95 loosely attached to the auger. When the arm 54 is in position on the auger it extends radially therefrom and is of such a length that it extends a distance beyond the uprights 15 of the rotary frame 14. The power 100 unit is started and the clutch lever 37 moved to bring the pulley 34 into operative engagement with the power unit, through the belt 36. The clutch mechanism 45 is operated by lever 46 to engage the lower portion of 105 shaft 42, and through pinion 44 rotate gear 20 and the rotary frame 14. The sliding sleeve 50 is disengaged from shaft 29, which shaft and the winding drum remain idle 110 and inoperative. The rotation of the gear 20 rotates the platform 16 and the frame 14, which are suspended from the axle 10 and at the top of the stationary frame 4 and the frame is maintained in position and alinement, as well as the gear 20 by the rim 115 or extension of the hub of the gear wheel rotating in the opening or bearing 2^a provided with the anti-friction rollers 25.

As the frame 14 is rotated the arm 54 which extends into the path of rotation of the frame will be engaged by one of the uprights and will rotate the auger. When the auger has descended its full operative depth the clutch 45 is disengaged through lever 46 with the shaft 42 carrying the pinion 44 125 and the rotation of gear 20, frame 14 and the auger stopped. The sleeve 50 is then moved into engagement with the shaft 29 which is thereby rotated through the pinion 30 and gear 28, and the hoisting cable 52 raises the 130

auger, the earth from the bore being drawn up from the bore with the auger.

When the auger is raised the sleeve 50 is disengaged to stop the winding mechanism. 5 The arm 54 is removed from the auger and an extension or boring rod 51^a having a square hollow end 51^b is fitted over the square end of the auger. Then the arm 54 is placed onto the added boring rod and the 10 auger and rod are lowered into the bore, clutch 45 thrown into engagement with shaft 42 carrying the pinion 44 and the gear 20 and frame 14 are again rotated which will rotate the auger by the frame contacting with the arm 54 on the boring rod which rotates the rod and the tool to which it is connected. The arm 54 is loosely mounted on the rod 51^a but is maintained in proper operative position by the pressure 20 exerted on it by the rotating frame.

After the boring rod has been added and the tool and rod are in position the guide plate 60 is swung down to rest across the opening 16^a with the boring rod resting in 25 the notch 62, and as the rod is rotated it will bear against the plate 60 and be maintained in alignment by the notch 62. When the boring rods and auger are raised by the winding mechanism the plate will be swung 30 open by the boring tool striking against the plate as the tool is raised and leave the opening 16^a unobstructed for the passage of the tool.

The foregoing operations are repeated 35 until the desired depth of bore is obtained. The operator can stand upon the platform 16 of the rotating frame, from which point he can operate the various clutch levers, and in some instances, depending upon the character 40 of the soil, the weight of the operator upon the rotating frame is desirable to cause a slower rotation of the boring tool, or the operator may stand upon the base of the truck, from which point he can operate the 45 clutch levers to operate the tool or raise and lower the same from the bore.

A boring machine embodying my invention, as described herein, can be transported with all the mechanisms in operative position 50 from one boring location to another and by lowering the auger the machine is ready to begin boring operations.

The rotary boring tool operating frame is suspended from, supported and rotatable 55 on, the axle at the top of the stationary tower and is maintained in alignment and against lateral movement by the depending rim confined in the bearing formed in the supporting structure at the lower end of the 60 rotary frame. The boring tool is guided by and maintained in alignment by the hollow hub and depending rim of the large gear wheel and in operative position is supported independently of the boring machine. After 65 the boring rods have been attached, the

guide plate 60 is swung into position and maintains the rods in alignment whereby the boring tool will cut a straight vertical bore.

It is evident that various changes, modifications and variations might be resorted to without departing from the spirit and scope of my invention and hence I do not wish to limit myself to the exact disclosures hereof.

What I claim is:—

1. A boring machine comprising a stationary frame, a frame rotatably suspended from said stationary frame, means adapted to rotate said suspended frame, and a boring tool provided with means engaged by 70 said suspended frame whereby said tool is rotated.

2. A boring machine comprising a supporting structure, a frame mounted on said supporting structure, a second frame rotatably suspended from said first mentioned frame, a bearing on said supporting structure in which said suspended frame is rotatably confined, means adapted to rotate said suspended frame, and a boring tool operated by said suspended frame.

3. A portable boring machine, comprising a wheeled supporting structure, a frame mounted on and fixed to said structure, a second frame rotatably suspended, from 85 said first mentioned frame, a power unit mounted on said supporting structure, means operatively connecting said power unit with said suspended frame, and a boring tool adapted to be operated by said suspended 90 frame when rotated by said power unit.

4. A portable boring machine, comprising a wheeled supporting structure, a vertical frame mounted on said structure, boring tool operating means suspended from said 105 vertical frame, a power unit mounted on and carried by said supporting structure, and means operatively connecting said power unit with said tool operating means.

5. A boring machine comprising a supporting structure, a frame mounted on said structure, and boring tool operating means suspended from and supported by said frame at its upper end and journaled in and confined against lateral movement at 115 its lower end in said supporting structure.

6. A boring machine comprising a supporting structure, a frame mounted on said structure, a boring tool operating frame rotatably suspended from the upper portion 120 of said frame and at its lower end confined against lateral movement by said supporting structure, and a boring tool provided with means adapted to be engaged by said rotatable frame whereby said tool is operated by said frame when rotated.

7. A boring machine comprising a supporting structure having a base with an opening, a vertical frame fixed on said base and extending above said opening, a boring 130

- tool operating frame rotatably suspended from the upper part of said fixed frame above said opening, and a boring tool supported in operative position independently of the operating frame, extending upwardly through the opening in the base and surrounded by the suspended frame, the boring tool provided with means adapted to be engaged by said operating frame whereby said tool is rotated by the frame.
8. A boring machine comprising a base having an opening therethrough, a fixed frame on said base extending above said opening, a boring tool operating frame rotatably suspended from the top of said fixed frame and above said opening, hoisting mechanism mounted on said suspended frame adapted to raise and lower boring tools through the opening from and to operative position, said suspended frame when rotated adapted to engage a boring tool to operate the same.
9. A boring machine comprising a supporting structure having an opening therethrough, a fixed frame mounted on said structure and extending upwardly above the opening, a boring tool operating frame rotatably suspended from said fixed frame and extending downwardly through the opening in the supporting structure, an annular gear mounted on the lower end of said suspending frame, a pinion in mesh with said annular gear, and means carried by said supporting structure to operate said pinion whereby said gear and suspended tool operating frame are rotated.
10. A boring machine comprising a supporting structure having a base provided with an unobstructed opening, a fixed frame mounted on said base and extending upwardly above said opening, a boring tool operating frame rotatably suspended from said fixed frame above said opening, said suspended frame terminating above the opening in said base and provided with a platform having an opening therethrough, an annular gear rigidly suspended from said platform below the base of said supporting structure, said gear having an unobstructed opening in alignment with the openings in said base and platform, means mounted on the supporting structure adapted to rotate said gear and suspended frame, and said suspended rotatable frame adapted to engage a boring tool in operative position extending upwardly through said gear, base and platform a distance within said frame.
11. A boring machine comprising a supporting structure having a base having an opening therethrough, a fixed frame mounted on said base, a boring tool operating frame suspended from said fixed frame and rotatable thereon, a platform provided with an opening mounted on said suspended frame above the opening in said base, a boring tool in operative position having its shaft extending upwardly through said base and platform and means carried by said suspended frame platform adapted to maintain the boring tool shaft in alignment.
12. A boring machine comprising a supporting structure having a base, a frame fixed to said base and extending upwardly therefrom, a boring tool operating frame rotatably journaled at its upper end to the upper portion of said fixed frame, and a boring tool, in operative position extending upwardly within said rotatable frame, said tool provided with a member extending radially therefrom adapted to be engaged by said journaled frame whereby said tool is operated during rotation of the frame.
13. A boring machine comprising a supporting structure, a frame mounted thereon, and boring tool operating means suspended from and supported by said frame and maintained in alignment by a bearing on the supporting structure.
14. A boring machine comprising a supporting structure, a fixed vertical frame mounted thereon, a boring tool operating frame suspended from and rotatable on said fixed frame, an annular gear mounted on the operating frame, tool raising mechanism carried by said tool operating frame, a pinion mounted on said supporting structure in engagement with said gear, and means for driving said pinion to rotate said gear and to operate said tool raising mechanism, said means comprising clutch mechanisms, whereby the rotation of said gear and frame may be stopped and the driving means engaged with the tool raising mechanism to raise the boring tool.

GEORGE F. ORMSBEE.
